[57] CLAIM

The ornamental design for a lighted cover for rectangular padlocks, as shown.

DESCRIPTION

FIG. 1 is a top, front, and right side perspective view of a lighted cover for rectangular padlocks showing my new design;

FIG. 2 is a bottom, rear, and left side perspective view thereof;

FIG. 3 is a right side elevational view thereof, the left side being a mirror image of that shown; and,

FIG. 4 is a bottom plan view thereof.
